CLAIM

The ornamental design for a faucet set, as shown and described.

DESCRIPTION

FIG. 1 is a front, left and top perspective view of the spout of the faucet set in FIG. 1.

FIG. 2 is a rear, right and bottom perspective view of the spout of the faucet set in FIG. 1.

FIG. 3 is a front elevation view of the faucet of FIG. 1.

FIG. 4 is a rear elevation view of the faucet of FIG. 1.

FIG. 5 is a left side elevation view of the faucet of FIG. 1.

FIG. 6 is a right side elevation view of the faucet of FIG. 1.

FIG. 7 is a top plan view of the faucet of FIG. 1.

FIG. 8 is a bottom plan view of the faucet of FIG. 1.

FIG. 9 is a front, left and top perspective view of the valve of the faucet set in FIG. 9.

FIG. 10 is a rear, right and bottom perspective view of the valve of the faucet set in FIG. 9.

FIG. 11 is a front elevation view of the valve of FIG. 9.

FIG. 12 is a rear elevation view of the valve of FIG. 9.

FIG. 13 is a left side elevation view of the valve of FIG. 9.

FIG. 14 is a right side elevation view of the valve of FIG. 9.

FIG. 15 is a top plan view of the valve of FIG. 9.

FIG. 16 is a bottom plan view of the valve of FIG. 9; and, FIG. 17 is front, left and top perspective view of a faucet set showing my design.

The dashed broken lines depict portions of the faucet set that form no part of the claimed design.
